DESIGN FOR A SLIDER BODY

Glen Holland, Bronxville, N. Y., assignor to Crown
Fastener Corporation, Warren, R. I., a corpora-
tion of Delaware

Application November 14, 1940, Serial No. 96,571

Term of patent 14 years

To all whom it may concern:

Be it known that I, Glen Holland, a citizen
of the United States, residing at Bronxville, in
the county of Westchester and State of New
York, have invented a new, original, and orna-
mental Design for a Slider Body, of which the
following is a specification, reference being had
to the accompanying drawing forming a part
thereof.

Fig. 1 is a face view of a slider body embody-
ing my novel design;

Fig. 2 is a side elevation of the slider body ap-
pearing in Fig. 1.

I claim:

The ornamental design for a slider body, sub-
stantially as shown.

GLEN HOLLAND.
